UNITED STATES PATENT OFFICE

EVERETT W. SWARTWOUT, OF WHITE PLAINS, NEW YORK

SIGNAL FOR TRAINS

Application filed June 9, 1924. Serial No. 718,733.

This invention relates to signals for trains.

An object of this invention is to provide

a signal for a train moving on a trackway, whereby indications are shown by the signal corresponding to the traffic condition, and the movement of the train, or adjacent train or trains, are controlled remotely from each train.

Another object of the invention is to provide a signal or set of signals, co-ordinated with blocks or sections of trackway, whereby the movement of the train and the signal indications are controlled remotely from the train.

15 A further object of the invention is to provide within the signal installation a member for controlling the movement of a train in correspondence to the indication of the signal.

The above and other objects of the invention are attained in a preferred form of the invention, comprising a signal installation, having one or more semaphores and an electrical resistance, inductance, transformer or equivalent train movement control member, embodied in the signal installation, whereby upon the setting of the signal to "caution" or "stop", the movement of the train is correspondingly controlled remotely from the train. In one form of the invention, the setting of a semaphore and control member for any signal is performed manually at the signal, and in another form of the invention the setting and operation of the semaphore and the control member of any signal is effected automatically, or under control at a central location.

Further features and objects of the invention will be more fully understood from the following detail description and the accompanying drawings, in which

40 Fig. 1 is a perspective elevation of a two semaphore signal, provided with manual operating members, and embodying my invention, the "danger" and the "caution" semaphores being shown in non-set or "clear" positions;

45 Fig. 2 is a similar perspective view of the signal shown in Fig. 1, but with the "danger" semaphore in set position and the "caution" semaphore in non-set position, the manual op-

erating members being in corresponding positions;

55 Fig. 3 is a similar perspective view, showing the "danger" semaphore in on-set position and "caution" semaphore in set position, and the manual operating members in corresponding positions;

60 Fig. 4 is a similar perspective view, showing both the "danger" and "caution" semaphores in set position and the manual operating members in like positions;

65 Fig. 5 is a detail vertical sectional view of Fig. 1, taken through the manual operating members, and on a greatly enlarged scale;

Fig. 6 is a sectional elevation on line 6—6 of Fig. 5;

70 Fig. 7 is a diagrammatic plan view of a series of blocks or track sections and signal circuit connections;

75 Fig. 8 is a front elevation of a single semaphore signal, showing a modification of the invention;

Fig. 9 is a sectional elevation of the modification shown in Fig. 8, taken on a line similar to that of Fig. 6;

80 Fig. 10 is a sectional elevation, similar to Fig. 6, but showing a further modification;

Fig. 11 is a diagram illustrating the application of my invention a loop trackway having two signals and providing for automatic control of the signals and of the train or trains; and

85 Fig. 12 is a diagram showing the application of my invention applied to a loop trackway and signal circuit connections, controlled from central location.

90 Referring to Figs. 1 to 4, inclusive, the signal proper may comprise a "danger" semaphore 16 and a "caution" semaphore 17, pivotally mounted at 18, 19 on suitable brackets (not shown) carried by a vertically extending casing 20. The base 21 of the casing 20 is of suitable form for positioning on a level support, as on the floor, table or the like in the use for toy electrical trains, or to be anchored by suitable anchoring pins in cement or the like, when applied to railway transportation.

95 A manual lever 22 serves to operate one of the semaphores, say semaphore 16, and an-

100 50 55 60 65 70 75 80 85 90 95 100

other manual lever 23 serves to operate another semaphore, such as the semaphore 17. A simple connection between the manual levers 22, 23 and the respective semaphores is afforded by fulcruming the lever 22, see Fig. 6, on the pivot 24, and connecting at a suitable leverage point 25 a rod 26, connected at its opposite end 27, see Fig. 1, to the leverage point 28 of the semaphore 16, the upper portion 27 of the rod 26 extending through the vertically elongated slot 27^a of the casing 20. Similarly, the manual lever 23 is fulcrumed at 29, connected at a suitable leverage point 30 to a vertically extending rod 31, which is connected at its upper end 32 at a suitable leverage point 33 of the semaphore 17. The rods 26, 31, are preferably bent at their lower ends, as indicated in Fig. 6.

Preferably, each semaphore is provided with visual indication, such as the transparencies 34, 35 for the "danger" signal 16, the transparency 35 being of red color or equivalent and the transparency 34 white or equivalent, the same cooperating with a lantern 36, usually an electric lamp bulb enclosed in a suitable housing on all sides excepting the side adjacent the semaphore 16. In toy electrical trains such lamp bulb is grounded at one contact.

The lower portion 37 of the casing 20 is provided with the slots 38, 39 to afford projection of the exterior portions of the levers 22, 23, to afford manual operation.

To the terminal 40, suitably located on and insulated from a base plate 41 is connected a lead 42, the other end of which is connected to the contact 43, located in coaction with a terminal bridge plate 44 of the lever 22. The body portion of the lever 22 may be of fibre or like insulating material, the object being that the terminal portion 44 of the lever 22 is of or carries a terminal bridge plate of a length to span the contacts 43, 45, when the lever 22 is in its raised position, as shown in Fig. 6, while insulation is provided against leakage of current through the pivot pin 24 or by the body portion of the lever 22 contacting with the frame 37. The contact 46 is positioned above the contact 43 an equal spacing, to be bridged by the terminal bridge plate 44 when the lever is in its downward or reversed position.

The manual lever 23 is constructed and coordinated with its set of contacts, similar as the manual lever 22. A contact 50 is spaced below a contact 51 to be spanned when the lever 23 is in its upper position by the terminal bridge plate 52; a contact 53 is spaced above the contact 51 to be bridged with the contact 51 when the terminal bridge plate is moved upwardly, i. e., upon the downward movement of the manual lever 23.

The contact 50 is connected by the lead 54 to the terminal 55, mounted on and insulated

from the base plate 41 of the casing of the signal.

Preferably, a resistance 56 is mounted within the casing 20 of the signal, and the resistance is conveniently in the form of a coil of suitable electrical resistance material and suitably supported in insulated relation with the casing 20. The lower end 57 of the resistance 56 is connected by the lead 58 to the contact 53.

The upper end of the resistance 56 is connected by the lead 59 to the contact 50.

The lead 60 connects the contact 45 of the manual lever 22 with the contact 51 of the manual lever 23. Accordingly, upon both levers 22, 23 are in their respective upper positions, as is indicated in Fig. 6, and assuming the current to enter at the terminal 40, the path of the circuit through the signal is by lead 42, contact 43, bridging element 44, contact 45, lead 60 contact 51, bridging element 52, contact 50, lead 54 and thence to terminal 55.

Upon moving the manual lever 22 to its downward position, whereat its bridging element 44 spans the contacts 43, 46, the circuit is traced as follows:—terminal 40, lead 42, contact 43, bridging element 44, contact 46, whereat the circuit is interrupted, and accordingly upon downward movement of the manual lever 22, the "danger" semaphore 16 is moved to its position as indicated in Fig. 2, in which circumstance as will be shown more fully in connection with the trackway shown in Fig. 7, the circuit for the section of the trackway effected, is devoid of current, causing the train to be brought to a stop, as explained more fully hereinafter.

Upon moving the manual lever 23 to its downward position, thereby bringing its bridging element 52 to span the contacts 51, 53 and assuming the manual lever 22 to be in its upper position, the circuit through the signal is traced as follows:—terminal 40, lead 42, contact 43, bridging element 44, contact 45, lead 60, contact 51, bridging element 52, contact 53, lead 58, resistance 56, lead 59, contact 50, lead 54 and thence to terminal 55. At these positions of the manual lever 22, 23, the "danger" semaphore 16 is in its non-set positions, see Fig. 3, and the "caution" semaphore 17 is in its set position, and accordingly, the current is reduced by the electrical effect of the resistance 56, or equivalent.

For both of the manual levers 22, 23 being in their downward positions, as is indicated in Fig. 4, and corresponding setting of the "danger" and "caution" semaphores 16, 17 the circuit through the signal is interrupted, namely by the absence of any electrical connection between the contact 43 and the contact 45.

The lighting indication of the semaphores 16, 17 is effected by means of any suitable elec-

trical lamp (not shown) connected at one terminal to one end of the lead 61, the other end of which lead 61 is connected to the terminal 40. The other terminal of the lamp is 5 grounded to the casing 20.

As indicated in Fig. 5, the contacts 45, 43 and 46 may be conveniently insulated by mounting on a strip 62 of insulation fibre, riveted or otherwise secured to the inner 10 face of the casing 20, which may be a metal stamping. Similarly, the contacts may be mounted on the fibre strip 63.

The semaphore 17 is similarly provided with transparencies 34, 35, showing white or 15 equivalent and green or equivalent in coaction with an electrical lamp (not shown) connected at one terminal by a conductor electrically connected in parallel to the lead 61 of the lamp of the semaphore 16, and its other 20 terminal connected by a conductor to ground.

Fig. 7 shows the employment of the form of signal shown in detail in Figs. 5 and 6. The trackway may be formed of any number of blocks, designated A, B, C, etc. The 25 "third" rail 66 of the block A is insulated from the "third" rail 67 from the block B by the insulating piece 68, preferably formed of insulating material, shaped at its opposite ends to be inserted within the registering 30 openings at the respective opposing ends of the "third" rails 66, 67 and which insulating piece preferably is formed with the projection 69, to space the opposing end of the "third" rail 66 from that of the "third" rail 35 67. Similarly, the opposing end of the "third" rail 67 is insulated and spaced from the "third" rail 70 of the block C by the insulating piece 71 having the projection 72. The connecting pieces 73 between the respective 40 outer rails 75, 75 of the blocks A and B serve to mechanically span the spacing between the opposing ends to afford smooth travel of the wheels of the locomotive and cars, or other vehicles and also to serve as electrical 45 conductors; similarly, the connecting pieces 73 mechanically and electrically bridge the spacing between the outer rail 74 of the block B and the outer rail 74 of the block C, likewise between the outer rail 75 of the block B 50 and the outer rail 75 of the block C.

It will be understood that the length and shape of the blocks or sections of trackway may be selected as desired.

The lead 76 is connected at its one end 55 to the "third" rail 70 of the block C and at its opposite end to the terminal 40 of the signal, which may correspond to the signal shown in detail in Figs. 5 and 6, and generally in Figs. 1 to 4, inclusive. The lead 78 is 60 connected at its end 79 to the "third" rail 67 of the block B and at its opposite end to the terminal 55. The lead 80 is connected at its end 81 to one of the outer rails (of the block C,) such as the rail 74, and at its opposite end 65 to the terminal 49 of the signal.

Assuming a train, whose wheels roll on the opposite outer tracks 74, 75 of the block A, and traveling in the direction of the arrow 81, see Fig. 7, and in the circuit of the trackway is included any suitable lead from a suitable 70 source to the "third" rail 66, thence through the usual brush contact carried by the locomotive, thence through the motor of the locomotive, the wheels of the locomotive and through a suitable connection (not shown) 75 in return to the source of electrical current.

If it is desired to stop the train in block B, the manual lever 22 is depressed to set the "danger" or "stop" semaphore 16, as shown in Fig. 2, and upon the train passing from 80 the termination of block A into block B, the circuit through the motor of the locomotive of the train is open circuited and de-energized by reason of the insulation of the third rail 67 at one end from the third rail 66 of the 85 block A and at its opposite end from the third rail 70 of the block C, and further by the reason of the open circuit between the contact 45, contact 43 and the bridge element 44 of the manual lever 22, as described more 90 fully hereinabove, and accordingly, the train will be brought to rest.

If it is desired to "slow down" the train when passing through the block B, the manual lever 23 is depressed, the manual lever 22 95 being in its elevated position, whereat the "caution" semaphore 17 will be set and the "danger" semaphore 16 is non-set, as indicated in Fig. 3, in which relation of the circuit, electrical power will be transmitted 100 from the third rail 70 of block C, through lead 76 to the terminal 40, lead 42, contact 43, bridge 44, contact 45, lead 60, contact 51, bridge 52 contact 53, lead 58, resistance 56, lead 59, contact 50, lead 54, terminal 55, 105 lead 78 to "third" rail 67 of block B, whereby the circuit through the locomotive includes the resistance 56 of the signal 21, and accordingly, decreases the amperage of the current 110 through the motor.

In the event that neither the manual lever 22 or the manual lever 23 is depressed and the semaphores 16, 17 are in non-set position, as is indicated in Fig. 1, upon the locomotive of the train passing from the block 115 A into the block B, the full circuit of the current is supplied to the motor by reason of the lead connection 76 with the "third rail" 70 of the block C at one end, thence through the signal 21 without transmission 120 through the resistance 56, namely to terminal 40, the lead 42, (see Fig. 6) contact 43, bridge 44, contact 45, lead 60, contact 51, bridge 52, contact 50, and upon the train passing through lead 54, terminal 55, lead 78 125 (see Fig. 7) to "third" rail 67, of block B, wiping contact of the locomotive, through the motor and the wheels to the outer rail 74, similarly as set forth hereinabove in relation to Figs. 5 and 6.

In the event that there is more than one train, the other train or trains are successively controlled by the manual setting of the signal. In the use of a series of signals on the trackway, the train or trains are respectively controlled by the setting of the signals affecting the sections of the trackway respectively controlled by the signals.

In Figs. 8 and 9 is illustrated a modification of a signal having a single semaphore 85 capable of "clear" setting 85^a, "caution" setting 85^b, and a "danger" setting 85^c, by manual operation of its setting lever 86 to the corresponding positions 86^a, 86^b, 86^c. The lever 86, see Fig. 9, is connected by the rod 87 to a suitable leverage point 88, see Fig. 8, relative to pivot 89 of the semaphore 86. The semaphore 86 may be provided with transparencies 90^a, 90^b, 90^c for the corresponding visual indication in coaction with an electrical lamp bulb mounted in the lantern casing 91. Coacting with the lever 86, pivoted at 92, and carrying a conducting bridge plate 93, is a set of contacts 94, 95, 96, 97. The resistance 56, or equivalent, may be mounted within the casing 20 of the signal, as set forth hereinabove.

The terminal 40 is connected by the lead 98 to the contact 96; the contact 95 is connected by the lead 99 to one end of the resistance 56, the opposite end of which resistance is connected by the lead 100 to the contact 97, which contact 97 is connected by the lead 101 to the terminal 55 of the signal. Accordingly, for the setting 85^c, the circuit is interrupted by the bridge 93 being out of contact with the contact 96 for the setting 85^b, the bridge 93 spans the contacts 95, 96, thereby interposing the resistance 56, similarly as respect to Figs. 5 and 6, and for the setting 85^a, the bridge 93 spans the contacts 96, 97, affording direct electrical conduction from terminal 40, lead 98, contact 95, bridge 93, contact 97, lead 101 to terminal 55.

The electrical connections of the terminals 40 and 55 with a series of blocks A, B, C, are similar as illustrated in Fig. 7, in respect to the signal shown in Fig. 6.

The terminal 49, of the modification of Figs. 8 and 9, is similar to terminal 49 of Figs. 6 and 7, to wit, for energizing the semaphore lamp or lamps by the connection of a lead 61, connected at one end to the signal terminal 40, thence to one terminal of the electrical bulb, grounded at its other terminal to the casing 20, thence from terminal 49, grounded to the casing 20, to lead 80, see Fig. 7, thence to return rail 74 to the source.

My invention is also applicable for continuous and automatical operation of the signals by the train or trains running on the tracks. Thus, for a trackway arranged as a loop or series of loops affording repeated return of the one or more trains, each train individual-

ly controls the signal of the section of two or more blocks of the trackway over which such train runs and effecting the stopping of a second train if present in the immediately rearward block and the "slowing down" of another train if present on the second rearward block by the control of the resistance or open circuiting of the energizing current.

Thus in Fig. 11, I have indicated a trackway formed as a loop and of a series of sections of blocks, the length and disposition of such trackway being capable of variation as may be desired. In Fig. 11, I have indicated two signals 105 of like construction and of like circuit arrangement with respect to series of blocks and a detail description of one signal and its circuit connections with the trackway will suffice, like reference characters being employed to indicate like parts.

Assuming that one or more trains to be placed on the trackway 106 and headed in the direction of the arrows 107. The blocks of any section are designated L, M, N. To effect the same the "third" rails 108L, 108M of blocks L and M are insulated from one another at any suitable limiting locations 109, similar to insulator 68 and the outer rails 110 of block M are similarly insulated from one another at the limiting locations 111; the outer rails of the sections N and M are insulated from the supporting ties. It will be understood that the "third" rail for the whole trackway is insulated from the supporting ties, and that the current is supplied from any suitable source connected to the leads 112, 113 respectively connected to the "third" rail 114 and to the outer rail or rails 115, of the general trackway.

The signal for such automatic operation is shown in Fig. 10 in details which are in modification of the construction shown in Fig. 6; the parts of Fig. 10 which correspond to like parts of Fig. 6 are designated by like reference numbers with the suffix "a," it being understood, however, that the levers 22^a, 23^a are preferably not operable manually and accordingly need not extend exteriorly of the signal casing 20. The lever 22^a is "depressed" to set its "danger" semaphore 16 by its solenoid 120, whose winding 121 is connected at one end by the lead 122 to the signal terminal 123 (see Fig. 11) energized by the lead 124 connected to the "third" rail 108M of the block M and the opposite end of the solenoid winding 121 is connected by the lead 125 to the terminal 126, (see Fig. 11) connected by the lead 127 to the "outer" rail 110 of the block M.

The signal terminal 49 is grounded to the metal casing 20 of the signal, thereby connecting in the grounded terminal of electric lamp, and connections are made with the signal terminal 40 to the other terminal of the electric lamp and with the track circuit to energize the lamp for all positions of the le-

vers 22^a, 23^a, similarly as for the levers 22, 23, of the arrangements shown in Figs. 6, 7, 8, and 9.

Accordingly, upon a train entering the block M, the circuit through the solenoid 120 is closed to set the "danger" semaphore 16 and automatically de-energizes the "third" rail 108L of the rearward block L. Such actuation of the lever 22^a may be effected by the core 128 of the solenoid 120 being suspended from the link 129, connected to the eye 130' of the lever 22^a. The spring 131' serves to return the lever 22^a to its non-set position upon de-energization of the solenoid 120.

The lever 23^a, see Fig. 10, is operated by its solenoid 130, whose winding 131 at one end is connected by the lead 132 to the signal terminal 123, see Fig. 11, connected by the lead 124 to the "third" rail 108M of the block M, and the opposite end of the solenoid winding 131 is connected by the lead 135 to the signal terminal 136, connected by lead 137 to the outer rail 110 of the block N. Upon actuation of the lever 23^a to its set position, its bridge 52^a is operated to span its contacts 51^a, 53^a and thus introduce the resistance 56 in the circuit of the "third" rail 108L and outer rail 115L of the block L, similarly as in the arrangement of Fig. 7, utilizing the signal shown in Fig. 6.

Accordingly, upon a train passing through block N, any train passing through block L will be energized to the reduced extent effected by the resistance 56. Connections with the "third" and outer rails of block M and an additional signal of like construction to effect de-energization of block M when a train is in block N, are similarly carried out.

In such arrangement as indicated in Fig. 11, in conjunction with Fig. 10, a trackway formed of blocks of different lengths may be placed in a show-window for demonstrating one, two or more toy electrical trains, the running of the trains and setting of the semaphores are controlled automatically. Such arrangement is highly advantageous for demonstrating purposes and to avoid collisions and de-railing, and particularly for toy trains, in which the motors may vary considerably in efficiency and consequent rate of travel for the same current.

In a similar manner, transportation trains for conveying persons and freight are controlled automatically by the traffic conditions in the advance blocks, and independently of the operation of the particular motors by the engineers of the trains. The arrangement is particularly advantageous by the absence of stop or trip levers on the trackway or other mechanical devices, as heretofore proposed.

The arrangement shown in Fig. 12 embodies the feature of central control of two or more trains in the respective sections of blocks of the trackway.

The central control is indicated at 140, and comprises a set of switch levers 141^a, 141^b, 141^c, 141^d, corresponding to the respective groups of blocks, each block being arranged similar to blocks L, M, N of the arrangement shown in Fig. 11 in conjunction with a signal of the type shown in Fig. 10; like parts are designated by like reference numbers. The switch levers 141^a—141^d are connected at their pivot points by a common lead 142 to the general outer rail 115 of the trackway.

The contacts 143^a—143^d are respectively connected by the leads 144^a—144^d to the outer rails 110 of the desired blocks, to wit, N, N, of the illustrated two sets of blocks. The connections with the blocks may be varied as desired.

Upon opening all the switches 143^a—143^d, the arrangement is in substance that of Fig. 11. However, upon closing any switch, say switch 143^b, and leaving the remaining switches 143^a, 143^c and 143^d open, thereby close-circuiting the therewith connected block M, and accordingly, if the train is in block L it is de-energized and brought to rest, with corresponding operation of the signal; upon closing the switch 143^a and leaving the remaining switches 143^b, 143^c, 143^d open, the train if in block L is slowed down, and corresponding operation of the signal, for the reasons set forth hereinabove.

Upon closing switch 143^b, with the switches 143^a, 143^c and 143^d open, assuming the train to be in block M, the signal will be set for "stop" indication relative to the block L and the train in block M will continue through block M into block N and thence into the succeeding blocks.

The arrangement of Fig. 12 is applicable for toy trains to afford control at a central location, in lieu of individual control at the respective signals as illustrated in Fig. 7, or automatic control is illustrated in Fig. 11.

The arrangement of Fig. 12 is also applicable for freight and other transportation electric railways from a central station, and independently of the control of individual operators on the respective trains, or when operated without individual operators on the trains.

It will be observed that the terminal 123 of each signal 105 of the systems illustrated in Figs. 11 and 12, corresponds to the terminal 40 of each signal of the system illustrated in Fig. 7, and that said terminals 123 and 40 respectively are connected to the current supply. If desired, the power lead from the current source may be directly connected to the terminals 40 of the signals of the system of Fig. 7, or similarly directly connected to terminals 123 of the signals of the systems of Figs. 11 and 12, as in the latter case by connecting each of the terminals 123 to the power lead, thus obviating the connection of each terminal 123 to a live third rail.

In the systems shown in Figs. 11 and 12, I have shown indicators 150 bearing the markings of any block or the adjacent blocks at the junctures.

5 Whereas, I have described my invention by reference to specific forms thereof, it will be understood that many changes and modifications may be made without departing from the spirit of the invention.

10 I claim:—

1. The combination of a trackway comprising a set of three sequential blocks, signals for said blocks, electrical supply means, circuit means for said supply means including a lead extending to the first block of said set of three blocks, electrically actuated means for said circuit means, an electrical resistance, and means responsive to the movement of a train in the third block of said set of three blocks for actuating said electrical actuating means to effect a corresponding signal actuation and connect said electrical resistance in circuit with said lead, and thereby reduce the current supplied by said current supply means to the trackway of said first block.

2. In a toy electrical railway, the combination of a tower of hollow construction, a semaphore pivotally mounted at an upper portion of said tower, an electrical resistance insulatingly mounted within said tower, a terminal insulatingly mounted on said tower, a lead connecting one end of said resistance with said terminal, a movable contact member co-operating with said terminal, and means connecting said semaphore with said movable contact member to thereby set said semaphore in positions corresponding respectively to the electrical connecting in and out of said electrical resistance.

3. In a toy electrical railway, the combination of a tower of hollow construction, a semaphore pivotally mounted at an upper portion of said tower, an electrical resistance insulatingly mounted within said tower, a terminal insulatingly mounted on said tower, a lead connecting one end of said resistance with said terminal, a movable contact member co-operating with said terminal, means connecting said semaphore with said movable contact member to thereby set said semaphore in positions corresponding respectively to the electrical connecting in and out of said electrical resistance and means for operating said movable contact member.

4. In a toy electrical railway, the combination of a tower of hollow construction, a semaphore pivotally mounted at an upper portion of said tower, an electrical resistance insulatingly mounted within said tower, a terminal insulatingly mounted on said tower, a lead connecting one end of said resistance with said terminal, a movable contact mem-

ber co-operating with said terminal, means connecting said semaphore with said movable contact member to thereby set said semaphore in positions corresponding respectively to the electrical connecting in and out of said electrical resistance and electrical means for operating said movable contact member.

5. A semaphore for a toy electric railway comprising a generally hollow base, a tubular tower extending thereabove, a semaphore pivotally mounted at an upper portion of the tower, a tube within the tower, an electrical resistance wound about the tube, a terminal located and insulated in the base, a lead connecting one end of the resistance with said terminal, a movable contact member co-operating with the terminal, and means connecting the semaphore with said movable contact member to set the semaphore and at the same time to place the resistance in or out of circuit.

In testimony whereof I have signed this specification this 14th day of May, 1924.

EVERETT W. SWARTWOUT.
